BALANCING TOY

William Gabriel Quick, Daisy, Tenn.

Application May 14, 1948, Serial No. 146,367

Term of patent 3½ years

(Cl. D34—15)

To all whom it may concern:

Be it known that I, William Gabriel Quick, a citizen of the United States, residing at Daisy, in the county of Hamilton and State of Tennessee, have invented a new, original, and ornamental Design for a Balancing Toy, of which the following is a specification, reference being had to the accompanying drawing, forming part thereof.

Figure 1 is a side elevational view of a balancing toy, showing my new design.

Figure 2 is a top plan view thereof, and

Figure 3 is a front end view of the same.

I claim:

The ornamental design for a balancing toy, as shown.

WILLIAM GABRIEL QUICK.
